Primary Examiner — Mojtaba Tehrani

(57) **CLAIM**

The ornamental design for a universal heated hand grip, as shown and described.

DESCRIPTION

FIG. 1 is a front-top-left perspective view of a universal heated hand grip showing my new design;

FIG. 2 is a front-bottom-right perspective view thereof;

FIG. 3 is a rear-top-right perspective view thereof;

FIG. 4 is a rear-bottom-left view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is an enlarged top plan view thereof;

FIG. 10 is an enlarged bottom plan view thereof; and,

FIG. 11 is a cross-sectional view taken along the line 11-11 in FIG. 5.

The broken lines showing an insulating pad in FIGS. 1, 2, 3, 4, 6, 9, 10, and 11, and portions of a plug in FIGS. 1, 3, and 9 are included for the purpose of illustrating environmental structure and form no part of the claimed design.
